MEASURING CUP

Clayton A. Laughlin, St. Paul, Minn., assignor to Brown
& Bigelow, St. Paul, Minn.

Application June 9, 1954, Serial No. 30,879

Term of patent 14 years

(Cl. D44—9)

FIG. 1.

FIG. 3.

FIG. 2.

FIG. 4.

To all whom it may concern:

Be it known that I, Clayton A. Laughlin, a citizen of the United States, residing in St. Paul, county of Ramsey, and State of Minnesota, have invented a new, original, and ornamental Design for a Measuring Cup, of which the following is a specification, reference being had to the accompanying drawing, forming part thereof.

Figure 1 is a side elevational view of a measuring cup showing my new design.

Figure 2 is a top plan view thereof.

Figure 3 is a bottom plan view thereof.

Figure 4 is a rear elevational view thereof.

I claim:

The ornamental design for a measuring cup, as shown.
